UNITED STATES PATENT OFFICE.

EDMUND O. SCHWEITZER, OF CHICAGO, ILLINOIS.

TRANSFORMER-POLE.

1,162,657.

Specification of Letters Patent. Patented Nov. 30, 1915.

Application filed January 2, 1913. Serial No. 739,624.

To all whom it may concern:

Be it known that I, EDMUND O. SCHWEITZER, a citizen of the United States, residing at Chicago, in the county of Cook and State of Illinois, have invented a certain new and useful Improvement in Transformer-Poles, of which the following is a full, clear, concise, and exact specification, reference being had to the accompanying drawings, forming a part of this specification.

My invention consists of a transformer pole used in the overhead distribution of current. This pole is preferably constructed of steel and is hollow so that the transformer may be placed near the bottom of the pole. I have provided a suitable opening in the pole which is closed by a door so that ready access may be had to the transformer and the fuse blocks which are supported by the pole. My invention obviates the necessity of placing the transformer at the top of the pole as is necessary in the present system of distributing current to consumers. The pole is arranged so that it forms the casing for the transformer and contains insulating oil which may be of any volume desired since there is provided available space for that purpose.

In one embodiment of my invention the secondary wires are connected at the top of the pole and lead downward to the transformer. The primary wires, on the other hand, which extend from the transformer, lead downward and are connected to the primary cable which is laid in a suitable conduit.

The advantage of my invention is that the appearance of the pole is greatly enhanced inasmuch as there are no objectionable features such as are present in the ordinary construction as now in use.

Another feature of my invention is that the transformer is protected from lightning to a large extent, owing to its position in the pole, and also to the fact that the pole which forms its casing is connected to the ground and therefore, acts to some extent as a lightning arrester.

My invention also provides an arrangement by which transformers can be easily

installed and removed with a minimum loss of time owing to the accessibility of the transformer near the base of the pole.

An additional feature which my invention provides is the fact that the capacity of the transformer per unit of active weight can be made relatively large owing to the large amount of space available for oil within the transformer pole.

My invention will be better understood by referring to the accompanying drawings in which—

Figure 1 is an elevational view of a pole embodying the features of my invention. Fig. 2 is a cross-sectional view taken on line 2—2 of Fig. 1. Fig. 3 is a cross-sectional view taken on line 3—3 of Fig. 2, some of the parts being removed in order to clearly show the arrangement. Fig. 4 is a cross-sectional view taken on line 4—4 of Fig. 2. Fig. 5 is an elevational view of the transformer forming part of my invention. Fig. 6 is an end view of Fig. 5, one of the shields being shown in cross-section. Fig. 7 is a bottom view of the transformer. Fig. 8 is a top view thereof. Fig. 9 illustrates the connections of the secondary wires with the secondary coils on the transformer. Fig. 10 is a diagrammatic view showing the three primary coils connected to the main supply wires and the two secondary coils having three lead wires extending therefrom. Fig. 11 is a top view of the connector which is disposed at the top of the pole and to which the secondary leads are fastened. Fig. 12 is a side view of the connector.

Referring now to Figs. 1 to 4 inclusive, I have shown a pole which has a lower section 13, an intermediate section of smaller diameter 14, and an upper section 15, of still smaller diameter, and a top section 16. Suitable connecting pieces are arranged between each of these sections so as to make the pole more or less ornamental, the whole constituting a rigid structure which is durable and serves the purpose of supporting the wires at the top and the transformer at the bottom. The top section of the pole has inserted therein a connector 17, as shown in Figs. 2 and 3.

It will be observed that there is a long

- bearing engagement between this section and the lowermost portion of the connector. This connector as shown in detail in Figs. 11 and 12, has an upper portion 19, which 5 has fastened thereto at different portions thereof plates 20, 21 and 22. Each of these plates is provided with a loop 23, extending into a recess in the portion 19, as shown clearly in Fig. 11, and these loops are 10 arranged to receive the ends of the connecting rods 24, which lead upwardly through the connector 17. This connector, it may be stated, may be of insulating material such as fiber or wood.
- 15 The plates, 20, 21 and 22, are held in position at one of their respective ends by bolts 25, 26 and 27, which pass through the connector 17, and at their other ends by bolts 28, 29 and 30. Four suitable connections 20 are thus provided for each plate, for the secondary lead wires which extend to the consumers. The bolts 28, 29 and 30 are held securely in the connector by means of suitable nuts 31, 32 and 33, which are disposed 25 at each side of the portion 19, and which are tightened against suitable washers so as to form a rigid connection. Similar nuts and washers hold the bolts 25, 26 and 27 in place. The connecting plates 20, 21 and 22 30 are provided with suitable openings, through which the bolts 25, 26, 27, 28, 29 and 30 are adapted to pass, as shown in Fig. 11, and in order to form suitable connection for the lead wires there are arranged nuts and washers at either end of each bolt.
- 35 The members 24, which pass upward through the connector are provided at their lower ends with suitable washers and nuts so that they may be properly held in place, and to form connecting means for the downwardly extending wires.
- 40 As shown in Fig. 11 and 12, there are three rods 24, to which three wires are connected, and which form a secondary cable 32, which leads down through an insulator 33, and is connected to the transformer as shown in Figs. 8 and 9. These connections are made with the secondary coils of the transformer as shown diagrammatically in 45 Fig. 10. The primary cable 33' extends upwardly through a pipe 34, and is connected at its lower end to the primary cable which is laid in a suitable conduit.
- 46 The upper end of the pipe 34, is secured 50 in a section 35, which is fastened in any suitable way to the end of the pole. Above the section 35, and secured in place in the pole is a table 36, which has extending therefrom a pipe 37, the connection of the pipe 60 with the table 36, being very tight so as to hold the oil 38, in the pole. This oil, as shown completely covers the transformer and acts as an insulating and cooling medium. The pipe 37, admits the primary cable 33', which leads upwardly and has a
- plus wire and a minus wire, each of which connects with the fuse blocks 39 and 40, these fuse blocks being secured to a bridge 41, which in turn, is fastened to the pole. These fuse blocks however, form no part of 70 my present invention and a detail description of them is deemed unnecessary. Suffice it to say however, that they are secured in position on the pole such that they are readily accessible when the door 42, is removed from the pole. This door is provided with a flange 43, which extends around the entire door and provides means whereby suitable screws may fasten the door to the pole. The lower end of the door has a lug 80 44, which projects downwardly and inside of one edge of the opening. At the upper portion of the door, a lock 45, is provided so that when the door is in position and locked, it will be impossible for anyone except the authorized person to open the same.
- 85 When desired, insulation 39^A such as fiber and the like may be provided on the inside of the pole and door so that when the fuses blow out any arcs which are formed will not be grounded through the metallic pole.
- 89 As shown in Fig. 3, section 16, has a member 46, in engagement therewith, which member is secured to a ring, 47. A semi-circular member 48, is provided with nuts 95 and bolts at either end thereof, which pass through the member 46, and serve the purpose of clamping the members 46 and 48, to the section 16 of the pole. The ring 47, is arranged to support a cap 49, as shown 100 in Fig. 2, which forms a protection for the connections. This cap 49, is provided with a plurality of slots 50, so as to admit the secondary cables as shown. These cables also pass through openings in the ring 47, 105 and are thus held in place.
- 110 Just below the door and situated above the level of the oil I have arranged a plate 51, which may be loosely supported in any suitable manner in order that it may be removed when it is desired to lift the transformer from the pole.
- 115 Referring now to the transformer shown structurally in Figs. 5, to 9, inclusive, and diagrammatically in Fig. 10, it will be observed that the transformer comprises a core 52, which has three primary coils, and two secondary coils disposed upon a bridge member 53. The core is supported by means of two pairs of angle-bars 54 and 55, which 120 are joined together at the bottom by suitable bolts 56 and 57, and at the top by bolts 58 and 59, so that the said angle-bars form a sort of framework for the core and coils. Shields 60 and 61, are retained upon the 125 angle-bars 54 and 55 by means of bolts 62, at the bottom and 63, at the top in such a way that they may be removed when desired. These shields form a protection for the coils when the transformer is lifted 130

from the pole and out through the opening closed by the door.

At the top of the said angle-bars 54 and 55, there are arranged suitable handles 64 and 65, which are held in place by bolts 58 and 59. These handles are adapted to be grasped when it is desired to remove the transformer. As shown in Fig. 7, the said angle-bars 54 and 55, have end portions at right angles thereto and which form flat surfaces engaging the table 36. The primary wires as shown in Figs. 6 and 8 are supported by pieces of fiber 66 and 67, these being held to the bolt 63, by means of screws 68, which pass through a clamping plate 69, and in to another plate 70.

On the opposite side of the transformer the secondary wires are supported by insulators 71 and 72, these being held in place upon the bolt 63, by means of clamping screws 73, which pass through a clamping plate 74, and into a smaller plate 75, these wires being connected with two secondary coils upon the transformer. It will be observed that this transformer does not occupy a great deal of space, and the arrangement is such that the oil 38, completely covers it.

As shown diagrammatically in Fig. 10 the transformer is provided with three primary coils, which may be connected either in series or in multiple, as desired, and there are two secondary coils which are arranged with three lead wires, which, as before described, lead upwardly through the pole and connect with the connector at the top thereof in order that consumers may be supplied with the current at the proper voltage.

It will be apparent that, instead of having merely the secondary wires leading up to the top of the pole, both the secondary and the primary wires may be connected at the top of such pole if desired, or the conditions may be reversed as shown in the drawings. The primary may be led up to the top of the pole and have suitable connections with the primary cable, and the secondary wires may be led down to the secondary cable which may be led in a conduit provided for that purpose.

The essential feature of my invention is to provide a pole which is ornamental in its nature, and at the same time is of a construction such as to completely inclose the transformer and the various connections to the overhead wires, and at the same time provide such a pole with ready means of access to such transformer and the connections, such as the fuse blocks connected therewith.

From the foregoing description, it will be seen that my invention comprises a transformer pole, in which the transformer is

disposed so that the pole acts to some extent as a lightning arrester, the position of the transformer being such that it can be easily installed and removed with very little difficulty. The arrangement is such that the capacity of the transformer per unit of active weight is relatively large owing to the large amount of space available for oil within the pole.

While I have described the specific embodiment of my invention, I do not wish to be limited to the precise construction shown, but desire to secure protection upon the feature of disposing the transformer within a pole and having such transformer suitably connected to any source of power in order to secure the lower voltage for use in distribution to consumers.

What I claim is:

1. In a system of alternating current distribution, the combination of an underground conduit, a long rigid upright hollow metallic pole, an alternating current transformer comprising an iron core bearing two inductively related windings, located within said pole, the said transformer extending upon certain radii substantially from one inner wall of the pole to the other and on other radii leaving substantial interstices between the transformer and the inner wall of the pole, conductors connected to one of the transformer windings leading through the hollow interior of the pole and from the base thereof into said conduit, and conductors connected to the other transformer winding leading through the hollow interior of the pole to the top of the pole and thence aerially to distant points, and a body of oil contained within the pole and in direct contact with the walls thereof and in which body of oil the transformer is immersed, whereby the transformer is protected from moisture within the pole and conduit and from lightning discharges into the pole, and whereby the heat liberated within the transformer is conveyed by convection currents of oil traversing said interstices from the transformer to the long upright metallic walls of the pole.

2. In a system of alternating current distribution, the combination of a long rigid hollow metallic pole adapted to be set upright in or upon the earth, an alternating current transformer comprising an iron core bearing two inductively related windings, located within said pole, primary and secondary conductors connected to said transformer windings leading from said transformer through the hollow interior of the pole, certain of said conductors extending aerially from the top of the pole to distant points, and a body of oil contained within the pole and in direct contact with the walls thereof and in which body of oil the trans-

former is immersed, whereby the transformer is protected from lightning discharges into said pole, and whereby the heat liberated in the transformer is conveyed by 5 convection currents of oil to the long upright metallic walls of the pole.

In witness whereof, I hereunto subscribe

my name this 27th day of December, A. D. 1912.

EDMUND O. SCHWEITZER.

Witnesses:
